US0D1029732S

(12) **United States Design Patent** (10) **Patent No.:** **US D1,029,732 S**
(45) **Date of Patent:** **** Jun. 4, 2024**

(54) **VEHICLE RACK**

(71) Applicant: **Extang Corporation**, Ann Arbor, MI (US)

(72) Inventor: **Cameron Warech**, Lawrenceville, GA (US)

(73) Assignee: **Extang Corporation**, Ann Arbor, MI (US)

(**) Term: **15 Years**

(21) Appl. No.: **29/894,555**

(22) Filed: **Jun. 12, 2023**

Related U.S. Application Data

(63) Continuation of application No. 29/813,393, filed on Oct. 28, 2021, now Pat. No. Des. 993,141.

(57) **CLAIM**

The ornamental design for a vehicle rack, as shown and described.

DESCRIPTION

FIG. 1 is a perspective view of a vehicle rack in a vehicle rack showing my new design.

FIG. 2 is a perspective view of the extrusion as shown separately for clarity; and,

FIG. 3 is a side elevational view of FIG. 2.

In the drawings, the broken lines depict environmental subject matter only and form no part of the claimed design.

1 Claim, 2 Drawing Sheets
